UNITED STATES PATENT OFFICE.

CARL AUGUST WINDEKNECHT, OF BERLIN, GERMANY.

BUILDING.

Application filed November 10, 1926. Serial No. 147,577, and in Germany October 14, 1926.

This invention relates to an arrangement, by means of which a covered room, entirely or partly provided with side walls, is instantaneously transformed into a free space, without disturbing its continuous utilization. The invention can be used for most various purposes, as for instance, hotel halls, factories, workshops, amusement halls and the like.

10 The spirit of the invention is to be found in the fact, that with most simple means, and without disturbance of its continuous use, roof and walls of a covered room, as far as they are provided, can be removed.

15 In the present case, wall and roof can be shifted or rolled aside simultaneously and independently the one from the other; whereby the subdivision or separations of the several parts can take place at will. The invention can be applied to most various places and has therefore a quite special value. The invention has the further great advantage to 20 make serviceable to the public those many grounds, which up to the present could not be used owing to fire-danger, hygienic reasons, police-regulations and the like.

25 In technical works, in which from time to time great quantities of steam or the like occur, or where, owing to an accident of some kind, poisonous gases occur in great quantity, the whole room can instantaneously be opened by means of the improved arrangement forming the object of the present invention, thus avoiding great accidents and 30 danger.

35 The present invention is further advantageous for lay-halls, cure places especially for pulmonics, because the hall can instantaneously be adjusted to the actual atmospheric conditions.

40 One form of execution of the object of the present invention is shown, by way of example, on the accompanying drawings, in which:—

45 Fig. 1 is a front elevation of a hall with closed walls and closed roof.

Fig. 2 a front elevation according to Fig. 1, the centre of the hall being transformed into an open free space.

50 Fig. 3 is a plan view of Fig. 1.

Fig. 4 a plan view of Fig. 2.

Fig. 5 is a section on line A—B of Fig. 3.

Fig. 6 a section on line C—D of Fig. 3, on enlarged scale.

55 Fig. 7 is a section through the guide-channel, on enlarged scale.

Fig. 8 is a front elevation of the automatic covering for the guide-channel when the central part of the hall is opened.

The hall shown by way of example in the accompanying drawings consists of the stationary side walls A—A', of the centre-walls B, B', of the stationary roof portions C, C', and of the displaceable roof portions D, D'.

The several parts are arranged in such a manner, that the roof- and wall portions to be displaced in one and the same direction, are made in one piece, that means, roof D and front wall B respectively D' and B' consist of a solid rigid frame, so that, when displacing one part of the subdivided portions, the part solidary with said first part will also be displaced simultaneously. One single driving means would be sufficient for displacing the roof- and wall portions; viz, the drive provided in the channel, as will be hereinafter more fully described. However, in order to avoid clamping of the several portions, there is further provided a roof-drive. The walls B, B' rest with their rollers o on guide rail p; for the roof-portions, a roller-guide o', p' (Fig. 3) is provided. At the top and bottom of the front walls B, B', bolts q, q' and r, r' are solidly fixed to a continuous driving chain, for instance a Gall's chain k respectively m.

The lower chain m (Fig. 7) is guided over chain- or toothed wheels s, s' and upon each of the toothed wheel axles, chain wheels t, t' are keyed, which latter engage with rolls or links u, u' of a continuous double chain, onto which links, chequered- or perforated sheet-iron plates v and the like are fixed (Fig. 8). It is to be understood that a device as shown in Fig. 7 is mounted once at the right hand side of the hall, and once at the left hand side thereof, viz, at s, s' (Fig. 1). Further it is to be understood that two continuous chequered-plated double chains are provided (Fig. 8), running the one over toothed double wheel I and chain wheels t, t' at the left hand side of the hall, and the other over toothed double wheel II and chain wheels t, t' at the right hand side of the hall. Chain m runs continuously over toothed wheels s, s', whilst the two chequered-plated double chains run in contrary directions; the one with regard to the other.

It will further clearly be understood that, when rolling the front walls B, B' together with roof-portions D, D' to the left and right hand sides of the hall, the open guide-

channel will automatically be covered by the continuous chequered-plated double chains, so as to shut the open guide-channel flush with the earth.

- 5 Underneath the roof a subdivided intermediary or auxiliary ceiling is provided, which serves as dust- or heat protector. The ceiling portions F, F' lay stationarily under the roof portions C, C', whilst the ceiling portions E, E', underneath the displaceable roof portions D, D', can be raised, by means of pulley- and cord arrangements or the like, in order that the portions E, E' may, when opening the centre part of the room, be 10 cased beyond the stationary roof portions C, C' simultaneously with the displaceable roof-portions D, D'. For this purpose a differential pulley *c* is driven, by means of a convenient hand-drive, or motor, *b*, which 15 pulley *c* rotates the rollers *e* and *f* by means of any suitable cord-arrangement.

With the object shown on the drawings, the intermediary central ceiling portions must be brought, prior to being displaced, 20 from their horizontal position into an angular position, for which purpose the differential pulley is applied, which pulley pulls the cord, running over roller *f*, quicker than the cord running over roller *e*, this in such 25 relation as is necessary for the purpose set forth (Fig. 6). The intermediary ceiling portions E, E' are thus brought into their correct position previous to their being laterally displaced simultaneously with the 30 roof-portions D, D'.

The displacement of walls B, B' and roof portions D, D' takes place, either by hand-drive or by motor *a*, which motor, by means of a shaft *g*, toothed wheels *h* and shaft *h'*, 35 rotate the chain wheels *i*, *i'* and *s*, *s'*, which latter also rotate the continuous chains *k*, *m*. Onto the upper chain *k*, the bolts or pins *q* and *r* are solidly fixed, and onto the lower chain *m*, bolts or pins *q'* and *r'* are 40 solidly fixed, thus securely conducting at top and bottom the portions to be displaced.

The driving means for displacing the walls and roof portions are provided at the front bottom part and rear upper part of the 45 hall. The front chain serves only to displace the front walls, whilst the rear upper chain serves to displace the roof portions simultaneously with the ceiling portions.

The gear-parts *b*, *c*, *e*, *f*, for raising and 50 lowering the ceiling portions E, E' are preferably fixed to the bottom surface of the displaceable roof portions (Fig. 6).

The drive for the front walls and for the roof can also, when roof and front walls do 55 not form a rigid whole, be separated by couplings, in such a manner, that both parts together, or each one for itself, may be displaced by means of one and the same driving means. The driving chains, as used in 60 the present case, for displacing the front

walls and roof-portions, run preferably continuously along the entire length of the hall, whilst the chains which carry the chequered plates for the guide-channel, are divided at the centre (Fig. 8) because these latter 70 chains have to run in contrary directions towards both sides.

I claim:—

1. In a building or the like having a plurality of fixed and movable wall and roof sections; means for displacing the movable wall sections in a plane parallel with the fixed wall sections; and means for displacing the movable roof section in a plane parallel with the fixed roof sections, whereby the building may be converted into a substantially free open space without disturbing its continuous utilization. 75

2. In a building as set forth in claim 1, the movable roof and underlying wall sections being rigidly connected together and movable as units and adapted to telescope the fixed roof and underlying wall sections. 80

3. In combination with a building as set forth in claim 1, said building having fixed ceiling plates mounted below the fixed roof sections, and ceiling plates vertically movably mounted beneath each movable roof section, and means for raising said movable plates out of engagement with the fixed ceiling plates prior to the displacement of the movable roof sections. 85

4. In a building as set forth in claim 1, said building having fixed ceiling plates mounted below the fixed roof sections; and ceiling plates vertically movably mounted below each of the movable roof sections; differential gearing and connections for raising and lowering the movable ceiling plates, the inner ends of the movable ceiling plates, 90 being raised and lowered at greater speeds than the outer ends thereof whereby the movable ceiling plates when raised will have the same pitch as the roof sections, for the purpose specified. 100

5. In a building as set forth in claim 1, said means comprising an endless chain mounted beside the wall sections; a second endless chain mounted besides the roof sections and means on the movable sections 105 engaging the chains, the adjacent sections being connected to opposite runs of the chains whereby the adjacent sections will be moved in opposite directions by said chains. 110

6. In a building as set forth in claim 1, the moving means for the wall sections being disposed in an open channel at the base of the wall of the building; and means connected with said moving means to automatically cover the open channel when the displaceable sections are being moved. 115

7. In a building construction or the like with several stationary and displaceable wall and roof-sections, means for displacing the 120

displaceable wall-sections with regard to the stationary wall parts; and means for displacing the displaceable roof-sections with regard to the stationary roof respectively, 5 wall sections whereby the building can be converted into a free open space without disturbing its continuous utilization.

8. In a building construction or the like with several stationary and displaceable wall 10 and roof sections, means for displacing the displaceable wall sections with regard to the stationary wall parts; and means for displacing the displaceable roof sections with regard to the stationary roof respectively,

wall sections whereby all parts can be displaced separately and independently the one from the other. 15

9. In a building construction or the like with several stationary and displaceable wall and roof sections, means for displacing the 20 displaceable wall parts with regard to the stationary wall parts, and means to enable the shifting of said wall sections the one over the other.

In testimony that I claim the foregoing 25 as my own, I affix my signature.

CARL AUGUST WINDEKNECHT.
